ANDRÉ BLONDEL, OF PARIS, FRANCE.

APPARATUS FOR EXCITING ALTERNATORS.

Application filed February 28, 1920. Serial No. 361,978.

To all whom it may concern:

Be it known that I, ANDRÉ BLONDEL, of 41 Avenue de La Bourdonnais, Paris, France, engineer, have invented new and useful Improvements in Apparatus for Exciting Alternators, which apparatus is fully set forth in the following specification.

This invention relates to means for exciting alternators which work either as generators or receivers (synchronous motors) the object being to reduce the amplitude of the oscillations to which they are subjected if coupled and the maximum current which they first deliver when accidentally short-circuited.

It is known that the armature reaction of alternating current generators produces a lowering of voltage at the brushes, when the machine works, this voltage drop being due to the wattless current-component.

Many authors, amongst which can be cited Rice, Blondel, Boucherot, Le Blanc, Danielson, Lunt, Latour, Johnston, Siemens & Halske, have previously proposed excitation-methods by which this effect may be annulled, by a compensation of the armature reaction obtained by different ways, and particularly by the use, as exciter, of a rotating converter, fed by a current furnished by transformers mounted in series or in shunt. This excitation means is well known, but the compensation of the armature reaction is objectionable for it increases the current intensity when a short circuit takes place; and increases the reactions of the coupled alternators.

I have discovered that in order to facilitate the parallel running of two or more alternators, for the feeding of a net, these alternators being actuated by reciprocating engines, it is advisable to reinforce as much as possible the armature reaction by the effect of the wattless current which run between machines.

My process is intended to be applied to alternators, the voltage of which is regulated by the variation of resistances inserted in the field windings. This resistance variation may be controlled automatically by known systems as those of Tirrill, Thury, Brown-Bovery, etc. In carrying out this process it is aimed to aggravate the armature reaction of an alternator without detracting from its voltage regulation, and with the aim to reduce the wattless currents exchanged by the transformers when they

work in parallel, and also to slow down and damp the local oscillations of the alternators.

Experience shows that the oscillations of alternators coupled singly or in parallel to the line and working as generators can be reduced by varying the inducing field in accordance with the variation of the direct reaction flux of the armature through the field circuits.

On the other hand experience has shown that on the sudden short-circuiting of an alternator the demagnetization of the field magnets under the effect of the direct reaction of the armature is retarded by the current induced in an unfavorable direction which this reaction generates in the exciting circuit. This unfavorable effect would evidently be reduced if at the same moment the variation of the current is made to cause an electromotive force of opposite sign to that which produces the diminution of flux by the induced field of flux traversing the primary circuit to act in the exciting circuit.

In both cases it will be seen therefore that it is desirable whenever the direct reaction of the armature causes a diminution of the flux of the field magnets to bring about an instantaneous diminution of the electromotive force applied at the terminals of the exciting winding of the field magnets, for this will cause a reduction of the current which normally passes from the exciter or from the exciter bars of the central station to the field magnets of the alternator.

The present invention consists in the addition to any exciting alternator of an arrangement for exciting which produces such instantaneous reduction of the electromotive force proportionally to the variation of the armature counter-ampere-turns opposed to the field magnets, in combination or otherwise with other processes for automatic relatively slow regulation of the field excitation which allow the difference of the potential at the terminals of the alternators or at a suitable point of distribution in the line fed by this alternator to be maintained constant between appropriate limits.

It will be well to explain here that numerous processes are known for such automatic regulation of the tension of an alternator excited by an exciter of ordinary type. In particular there may be cited the automatic regulators of Thury and of Tirrill as characteristic types of apparatus for obtain-

ing the object desired by different means. Thury's process consists in the automatically actuated rheostat controlled by a simple or compensating voltmeter (compensated by the current in such a manner as to take into account the loss of line tension); so soon as the tension of distribution falls below the fixed value, the handle of the rheostat comes automatically into action in such manner as to lessen the resistance of the exciting circuit of the alternator until the tension has regained its normal value; the rheostat is operated in inverse direction if the tension rises above the desired value.

15 In the Tirrill process the same result is obtained by means of a trembler or of a contact which short-circuits and introduces a resistance mounted in series in the exciting circuit; the ratio of the durations of closing to the durations of opening being modified to obtain a larger or smaller exciting current. This ratio is also constantly regulated by an electro-magnet placed under the control of the tension of distribution.

20 25 These regulating apparatus or any other analogous apparatus may be interpolated, for example, in one of the exciting circuits of the exciter which delivers current to the circuit of the field magnets of the alternator.

30 According to the present invention, an exciter of the ordinary type of alternators is modified by providing it with a counter-compounding arrangement, that is to say an arrangement which produces the inverse effect to that which is instantaneously produced in compound excitors by the action of the current delivered by the alternator. The most simple method of obtaining this result in the general case of a polyphase alternator having any desired number of phases, consists, for instance, in interpolating in each of the conductors passing from the alternator, the primary of a series-transformer analogous to those employed for 40 45 50 compounding alternators and in causing the secondary circuits of each of these transformers to act in the opposite direction to that which would be required to produce the compounding (that is regulation of the tension).

In the accompanying drawing:

Figs. 1 to 5 illustrate diagrammatically some methods of carrying out the invention.

55 Fig. 6 shows the rheostats of a Thury regulator.

A is the armature of the alternator (for the sake of clearness, it is supposed to be a monophase alternator); M is the inducing circuit; f_1 , f_2 are wires leading from the alternator and corresponding to one of the phases; B_1 , B_2 are the alternating current bus bars of the central station generator or a portion of the central station; f_3 , f_4 are wires leading to a second alternator coupled in parallel with the alternator A; B_3 , B_4 are

collecting bars located at some other point from which pass the feeders at the outlet of the generating station; B_5 , B_6 are bars which may be provided for collectively exciting with alternating currents the rotary converters or converters of several alternators working in parallel. B_7 , B_8 are bars for collectively exciting with continuous current either the alternator or the counter-compounding rotary converter; L_1 , L_2 is a portion of the line.

75 E_1 is a counter-compounding rotary converter (or the dynamo in Fig. 4), of a suitable type; J_1 , J_2 its field magnet; b_1 , b_2 , b_3 , b_4 are the rings of the ordinary winding of the armature or of a winding superimposed on the same armature of the rotary converter E_1 ; E_2 is a rotary-converter or a dynamo; J_3 , J_4 are its field magnets; b_5 , b_6 the rings of the converter E_2 alternating current side; C_1 , C_2 are a pair of two direction contacts; N is a battery of accumulators.

80 D_s is a counter-compounding series transformer; D_p a transformer connected in parallel with the wires f_1 , f_2 of the alternator or with a group of bus bars B_1 , B_2 or B_3 , B_4 ; D_e is an exciting transformer whose primary is in series with the exciting circuit of the alternator and whose secondary feeds a special circuit placed on the field magnets on the exciter E_1 (or of the exciter E_2 in Fig. 3); R_1 , R_2 , R_3 , R_4 are exciting rheostats; S is a reactor, T_1 , T_2 are automatic excitation regulators; of course only one of these automatic regulators is provided 90 for each alternator or for each group of alternators working in parallel; the diagram shows two examples of the arrangement. K_1 , K_2 are switches which serve to cut out the unused regulator; P is a tension limiting arrangement or discharger of a known type seen in Fig. 3 only, but which may be introduced in any other arrangement. I is a circuit breaking switch controlled by windings m_1 or m_2 and by the transformer 95 D ; it breaks the exciting circuit in the case of an undue output from the alternator; it may be provided in any of the arrangements.

100 Fig. 1 shows an arrangement which may be adopted when each alternator at a generating station is provided with a counter-compounding exciter fed on the alternating current side with current resulting from two 110 transformers, series and parallel.

115 Fig. 2 shows the employment of a similar counter-compounding rotary converter but having two alternative windings fed respectively from two separate circuits, one derived from a series transformer, the other 120 from a transformer fed in derivation.

125 Fig. 3 corresponds to the case in which the counter-compound exciter whose armature receives alternating current from a counter-compounding transformer is itself excited 130

partly in shunt (or in series) partly from an independent excitation which may be derived from a battery of accumulators, a dynamo or a rotary converter.

5. For instance, the compounding effect is produced by a dynamo E_1 of any type whose armature is in the exciting circuit of the alternator and whose field is fed from any source as for example from dynamo E_2 .
10. This dynamo E_1 is thus excited from an independent circuit and the rings b_1 b_2 of its armature are connected to the transformer in series with the circuit of the alternator in such a manner as to produce a magnetic 15 effect opposite to the field produced by the independent exciter circuit.

Figs. 4 and 5 show special exciting windings which augment the apparent self-induction of the field circuits and which may respectively be adapted to the arrangement shown in Figs. 1, 2 and 3.

In all these figures, the circuit of the alternator is supposed to be monophase for the sake of clearness, but usually the alternator will be provided with any desired 25 number of phases and poles. In the same way, the counter-compound transformer may have any number of phases and feed a corresponding number of phases of any of 30 the rotary converters shown.

When the transformer D_p is common to several alternators working in parallel, its secondary is connected to the exciting bars B_5 B_6 from which the wires which feed respectively each of the excitors E_1 on the alternating side lead to the rings b_1 b_2 in the case of Fig. 1, to the rings b_3 b_4 in the case of Fig. 2, and to the rings b_5 b_6 (Fig. 3) for a rotary converter E_2 of any type which 40 may be provided for the purpose of producing a continuous independent excitation of the exciter E_1 .

There exist three main types of known arrangements of compounding converters; a first which utilizes for its alternate current feeding of the armature the tension derived from the transformer D_s and from the transformer D_p (Fig. 1). The compounding windings may be distinct from the winding 45 which delivers continuous current (Leblanc type for example). A second which receives in two separate windings on the armature, currents produced respectively by the two electromotive components of the transformers D_s and D_p (Fig. 2). A third which only utilizes on the alternating side-current produced by the tension of the series transformer (Fig. 3).

According to this invention, one or 60 other of these arrangements is modified by inverting the direction of the connections of the secondary of the series transformer with respect to the rings b_1 b_2 . The degree of counter-compounding may be regulated by 65 varying the electromotive force produced in

the secondary of the series transformer; this may be effected by varying the ratio of transformation in any of the well known ways.

Of course, all phases should be regulated 70 in the same manner; one phase only is shown in order to simplify the figures.

The position of the armature of the exciter or rotary converter E_1 on the shaft of the alternator with which it is fast is regulated 75 in such a manner that the field produced by the compounding currents (that is to say by the currents which are in phase opposite to those of the primaries of the series transformer) is in direct opposition 80 with the normal inducing field of the exciter; this therefore acts as counter-compounding.

The continuous excitation of the exciter E_1 may be effected in series or in shunt (but 85 preferably in shunt in the arrangements shown in Figs. 1, 2 and 3) by the circuit passing from the brushes of the commutator.

The exciter may be stabilized by providing it with a continuous supplementary excitation through an independent circuit. 90 This independent excitation may be derived for example from an exciter E_2 arranged in each alternator; but usually it would be common to a portion or to the assemblage of 95 the station alternators working in parallel.

This allows the exciter E_2 to be actuated by a shaft independent of that of the alternator; it may be driven by an asynchronous or synchronous motor or may itself be a rotary converter receiving alternating current derived from a transformer in shunt as shown in Figs. 3 and 4; in this latter case only it is provided with rings b_5 and b_6 .

In all the preceding arrangements there 105 may be provided another partial excitation of the exciter E_1 caused by variable currents generated in the exciting circuit of the field magnets of the alternator during the oscillations of this latter or when a sudden overcharge (flow of current) occurs. This exciting winding is shown diagrammatically in Figs. 5 and 6 in which it is shown alone in order to simplify the diagrams; it may how-

ever be superposed on the other field magnet windings or may replace one of them. The exciter thus counter-compounds itself but only for variation in speed of the alternator which it excites because the induced 110 currents have the frequency of the hunting oscillations of the armature of the alternator about the mean speed, finally this winding produces for its frequency the same effect as that of a self-induction interpolated in the circuit of the field magnets. Of

course a resistance is introduced into this inducing circuit sufficient to enable the current produced to be substantially in phase with the electromotive force induced in the 115 secondary of the transformer D_s . This sec-

ondary of the transformer D_s has the same frequency as the hunting oscillations of the armature of the alternator about the mean speed, finally this winding produces for its frequency the same effect as that of a self-induction interpolated in the circuit of the field magnets. Of

course a resistance is introduced into this inducing circuit sufficient to enable the current produced to be substantially in phase with the electromotive force induced in the 120 secondary of the transformer D_s . This sec-

ondary may feed the exciting circuit of E_2 in place of E_1 when there is an exciter E_2 ; the effect produced remains of the same nature.

- 5 Alternators thus compounded may also advantageously be employed to reduce the effects of short-circuiting; directly a short-circuit in the line or in the wires connecting the alternators to the bars takes place, the 10 counter-compounding series transformer D_s delivers an intense demagnetizing current into the armature of the exciter whose tension will be reduced. This effect is again increased by the influence of the excitation in 15 shunt. The exciter will thus aid in the demagnetization of the field magnets which tends to cause the armature reaction of the alternator but which is hindered when there is no counter-compounding and this will take 20 place mainly at the commencement of the short-circuit by the sudden increase of current in the field magnets,—the well known phenomenon discovered by Dr. Punga.

The presence of a reactor S reduces such 25 afflux of current and favors the fall of tension at the brushes of the exciter.

Counter-compounding allows alternators to be more economically constructed as the gap may be reduced and therefore the am- 30 pere-turns on its field magnets.

It may be objected that this arrangement increases to a greater or less extent the variations in voltage in function of the load above all when the current produced by the 35 alternator is wattless. In order to compensate for this increase of variation there may be added to the arrangement a tension regulator of one of the known types (see what has been stated above); this regulator has its 40 main circuit interpolated in series either in the excitation circuit of the exciter E_1 , or in the excitation circuit of the exciter E_2 . In both cases, the effect of the automatic regulator is progressively to modify the tension 45 at the terminals of the field magnets of the alternator in such a manner as to re-establish the desired tension of distribution in spite of the contrary effect of the counter-compounding exciter. In order to avoid in 50 the case of a short-circuit the automatic regulator counterbalancing excessively the effect of the counter-compounding exciter, such automatic regulator is regulated in such a manner that in normal working it 55 can only deliver to the alternator an exciting current not greater than that which the largest output requires; there may even be added to the automatic regulator a working terminal which cuts out its circuit or which 60 interpolates in its circuit a very large supplementary resistance as shown at R_4 in Figs. 4 and 5 in which the rheostat of a Thury regulator is shown diagrammatically so that after having increased the excitation 65 to a very high value the automatic regulator

continuing its action suddenly reduces the excitation to a minimum value.

When these automatic regulators are placed in the position T_1 , Figs. 1 to 3, it may also be desirable that they should have a 70 sufficiently slow action or even be retarded by some arrangement in order to prevent their action from being felt during the duration of the variation of the exciting current produced in conformity with this invention by the counter-compounding arrangement.

What I claim as my invention is:

1. Means for controlling the frequency and the amplitude of oscillations due to 80 hunting of a system of alternators feeding busbars in parallel, comprising a series transformer inserted in the mains of the alternator, a commutator machine connected to the secondary circuit of the series transformer, 85 said commutator machine feeding the field coils of the alternator or alternators and providing a counter-compounding action in such manner that an instantaneous increase of the series watt current exchanged between the alternators causes an instantaneous diminution of the field current and automatic slow-acting means for compensating for disturbance of the busbar voltage attendant upon the action of the devices responsive 90 to current exchanged between the alternators.

2. Means for controlling the amplitude and frequency of oscillations due to hunting of a system of alternators feeding busbars in parallel, comprising a series transformer inserted in the mains of the alternator, a commutator machine connected to the secondary circuit of the series transformer, 100 said commutator machine feeding the field coils of the alternator or alternators and providing a counter-compounding action in such manner that an instantaneous increase of the series watt current exchanged between the alternators causes a diminution 105 of the field current, combined with means for regulating the transformation ratio of the series transformer, and with an automatic slow-acting field control device for restoring at the busbars the proper regulation 110 of the distribution voltage.

3. Means for controlling the amplitude of oscillations due to hunting of a system of alternators feeding busbars in parallel, comprising a series transformer inserted in the 120 mains of the alternator, and a commutator machine connected to the secondary circuit of the series transformer, said commutator machine feeding the field coils of the alternator or alternators and providing a counter-compounding action in such manner that an increase of the series current causes a diminution of the field current, combined with means for stabilizing the excitation of the exciter in normal working, said means 125 130

comprising a separate field magnet winding placed on the field magnets of the exciter and means at the generator station for supplying an independent exciting current to such winding.

4. Means for controlling the amplitude of oscillations due to hunting of a system of alternators feeding busbars in parallel, comprising a series transformer inserted in the mains of the alternator, and a commutator machine connected to the secondary circuit of the series transformer, said commutator machine feeding the field coils of the alternator or alternators and providing a counter-compounding action in such manner that an increase of the series current causes a diminution of the field current, combined with an automatic voltage regulator for correcting the mean value of the variations in voltage independently of the periodic variation produced by the said oscillations due to hunting.

5. Means for reducing the amplitude and frequency of the free oscillations of alternators coupled to one another, comprising an exciter for each alternator and means for producing an instantaneous reduction of the electromotive force of said exciter proportionally with the variations of current exchanged between machines and armature counter ampere turns opposed to the field magnets substantially as described.

6. Means for reducing the amplitude and frequency of the free oscillations to which alternators are subjected when coupled or the maximum current which they first deliver when accidentally short-circuited, comprising means for transforming current exchanged between the machines and means for utilizing the transformed current to produce an instantaneous reduction in the field excitation of an alternator.

7. Means for reducing the hunting action of alternators coupled in parallel or the maximum current delivered when short-circuited, comprising means for transforming alternating current exchanged between the alternators and means for utilizing the transformed current to produce a diminution of the exciting current of an alternator.

8. The combination with a system of alternators having fields each excited by a current from a rotary converter, means for transforming current flowing in series between the alternators and means for utilizing the transformed current to cause diminution of said exciting current in accordance with an increase of said series current thereby controlling the amplitude and frequency of the free oscillations due to hunting action of the system.

9. The combination with an alternator,

of a compound exciter therefor, means for instantaneously producing a diminution of the electromotive force applied at the terminals of the exciting winding and field magnets by the action of the increased current delivered by the alternator and means for producing automatic, relatively slow regulation of the field excitation to maintain the difference of potential constant.

10. The combination with an alternator, of a counter-compounding exciter and a series transformer feeding current to the exciter, said exciter acting on sudden increase of or diminution of series current to cause an instantaneous diminution or increase of the field current in combination with a slow-acting controlling device for the field excitation of the alternator producing a slow increase or decrease thereof.

11. The combination with an alternator, of a rotary converter operated by alternating current and supplying exciting current for the alternator field, a transformer in a series connection from said alternator to the mains, a transformer in parallel or connected across the terminals of the machine and connections between the secondaries of said transformers and the alternating side of the converter to feed said converter with current compounded from said transformers, and an independently acting automatic self-excitation regulator for the field of said converter acting oppositely to said compound ing device.

12. The combination with an alternator, of a rotary converter supplying exciting current for the field alternator and fed on its alternating current side with current from transformers, series and parallel, an automatic self-excitation regulator for the field of said converter and a continuous supplementary excitation through an independent circuit for stabilizing the exciter.

13. The combination with an alternator, of a rotary converter feeding the field of the alternator, a series transformer inserted in a main of the alternator and feeding alternating current to the alternating side of the rotary converter, said converter supplying diminishing current to the field of the alternator on increase of series current in the transformer and means for partially exciting the field of the rotary converter by variable currents generated in the field magnet circuit of the alternator by oscillations of the alternator or sudden overcharge.

In testimony whereof I have signed this specification.
